UNITED STATES PATENT OFFICE.

LUCIAN M. FOSTER, OF TROY, NEW YORK, ASSIGNOR TO BENJAMIN POOLE,
OF TOPSFIELD, MASSACHUSETTS.

REGISTERING AND CANCELING BALLOT-BOX.

SPECIFICATION forming part of Letters Patent No. 408,093, dated July 30, 1889.

Application filed April 11, 1889. Serial No. 306,768. (No model.)

To all whom it may concern:

Be it known that I, LUCIAN M. FOSTER, a resident of Troy, in the county of Rensselaer and State of New York, have invented certain new and useful Improvements in Ballot-Boxes; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in ballot-boxes; and it consists of the novel construction and combination of parts hereinafter described, and pointed out in the claims.

Figure 1 of the drawings is a top plan view of my improved ballot-box with the cover removed, showing the canceling and registering attachments in plan. Fig. 2 is a vertical sectional view taken on the broken line $x-x$ in Fig. 1, looking in the direction of the arrow, with the cover on, and showing the rolls in end elevation. Fig. 3 is a similar sectional view on the line $y-y$ in Fig. 1, and showing the cam in end elevation. Fig. 4 is an end view in elevation of the crank C^7 and spindle C^2 .

A is a rectangular case or box having a lower chamber A' , which serves as a receptacle for ballots, and an upper chamber A^2 , which contains the canceling and registering devices. The cover of the upper chamber is removed from the box, as shown in Figs. 1 and 2, with a perforation A^3 , adapted to receive the ballots as they are fed through the same to the feed-roll B and the register-roll C. I have shown the feed-roll fixed upon a spindle B' , which has suitable bearings on the frame A^4 , surrounding the opening A^5 , which opening affords a means of communication between the two chambers of the box. The spindle B' may have a stem B^2 , adapted to receive an operating-wrench, or it may be operated in any well-known manner. The feed-roll may also be provided with a suitable ink-canceling surface, as the letters "Troy," adapted to

press the ballot against the register-roll. These letters are inked by the ink-roll B^3 . The register-roll is provided with a pair of toothed rims C' , adapted to overlap the flange B^4 on the feed-roll and engage with the ballots which are fed in between the two rolls. The register-roll is fixed upon the spindle C^2 , which has suitable bearings upon the frame A^4 . This spindle is provided at one end with a pinion C^3 , adapted to engage with the gear-teeth C^4 of the registering-dial C^5 , fixed upon shaft C^6 , rotary in suitable bearings in the frame A^4 . I have shown a single dial; but it is obvious that any known form of registering device may be used. The opposite end of the spindle C^2 is provided with a wrist or crank C^7 , controlled by a spring C^8 , secured at one end to the crank and at the other end to some fixed object, as the side wall of the case at C^9 , so that the crank cannot be moved without opposing the resilient force of the spring. The spindle C^2 is also provided with a cam D , fixed thereon to engage with the lever D' , pivoted upon the frame at D^2 and controlled by spring D^3 . The lever supports the wire stem D^4 of the bell-hammer adapted to strike the bell D^6 , secured upon the case.

The operation of the device is as follows: A ballot is inserted through the opening A^3 and its inner end pushed down between the feed-roll and the register-actuating roll. The feed-roll is then given a rotary movement, which feeds the ballot down through the opening A^5 into the chamber A' or ballot-box proper, and at the same time prints upon one side of the ballot the word "Troy." The teeth in the rims C' also make two parallel rows of indentations the length of the ballot—one on each side of the printed word. The cam D also acts upon the lever D' to raise the bell-hammer, and as the cam slips from the end of the lever the spring D^3 suddenly forces the lever back again to the position shown in the drawings, causing the hammer, supported by the yielding wire D^4 , to strike and ring the bell or gong.

It will be observed that the feed-roll does not at any time directly engage with the register-actuating roll. Consequently the latter is only actuated by the ballot, and is prefer-

ably made of such a size that its circumference is about measured by the length of a ballot. Then each ballot forced between the rolls and engaging with the toothed rims C' 5 will give the register-roll approximately one revolution. The pinion C³ and gear C⁴ are so proportioned that one revolution of the register-roll moves the dial through one space.

Should it happen that the length of the ballot was sufficient to give the roll more than one revolution—as, for example, one and a quarter revolution—the spring C⁸ would immediately force the roll back again to just one revolution. Likewise, if the length of the ballot 15 was not sufficient to give the roll a complete revolution, the spring C⁸ would complete the revolution. This will be fully understood upon inspection of Fig. 4. The broken circular line in such figure represents the path 20 of the wrist-pin. Now, it is evident that if the register-roll should be revolved until the wrist-pin reached the point *a* and then released, the spring C⁸ would restore the parts to the position shown, the pin passing back 25 over the same course it traveled in reaching *a*; but if the force was continued until the pin had traveled through more than half a revolution—for example, to *b*—and withdrawn, then the spring would complete the 30 revolution and restore the parts to the position shown; also, if the revolving force was continued through a whole revolution and nearly half another, as around to *a*, and then withdrawn, the spring would restore the 35 parts to the position shown, the register-roll being credited with only a single revolution on the dial.

A spring-controlled roll is preferable to a weight-controlled roll, for the reason that less 40 room is required to operate it and the control is not influenced by the position of the inclosing and supporting case.

It might happen that unless the ballot was

continuously pushed down into the opening A³ the feed-wheel would slip on the ballot when rotated without drawing the same in between the two rolls. For the purpose of overcoming any such difficulty I provide the periphery of the feed-roll with a peripheral lug or projection F, adapted to engage with 45 the periphery of the register-roll, and by reason of its frictional contact therewith cause the latter roll to revolve through a small arc proportional to the length of the lug, which 50 positively starts the ballot in between the 55 rolls.

What I claim as new, and desire to secure by Letters Patent, is—

1. In a ballot-box provided with ballot-cancelling attachments, the combination, with a 60 feed-wheel, type-wheel, and type-inker, of a register-roll, parallel toothed rims on such roll, and a peripheral lug on one of such rolls adapted to frictionally engage with the periphery of the other roll, substantially as de- 65 scribed.

2. In a ballot-box provided with ballot-registering attachments, the combination, with a 70 feed-roll, of a ballot-actuated registering-roll and spindle, spindle-crank, crank controlling and actuating spring, and a roll-and-spindle-actuated registering-dial, substantially as de- 75 scribed.

3. In a ballot-box provided with registering attachments, the combination, with the feed- 80 roll and register-roll, of a peripheral lug on the feed-roll, adapted to frictionally engage with the periphery of the register-roll, substantially as described.

In testimony whereof I have hereunto set my hand this 26th day of March, 1889.

LUCIAN M. FOSTER.
